Primary Examiner — John Windmuller*Assistant Examiner* — John R Yeh(74) *Attorney, Agent, or Firm* — Ntellect Law, P.C.(57) **CLAIM**

The ornamental design for a floor cleaning device, as shown and described.

DESCRIPTION

FIG. 1 is a perspective view of a floor cleaning device in accordance with one embodiment of the present design;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1;

FIG. 6 is a top plan view of FIG. 1; and,

FIG. 7 is a bottom plan view of FIG. 1.

The broken lines in the drawings are for illustrative purposes only and form no part of the claimed design.

1 Claim, 6 Drawing Sheets(56)
